UNITED STATES PATENT OFFICE.

MICHAEL WOODS, OF CARLTON, AND THOMAS JEFFERSON GILBERT, OF BRUNSWICK,
VICTORIA, AUSTRALIA.

MACHINE FOR DRESSING RAILS.

1,027,366.

Specification of Letters Patent.

Patented May 21, 1912.

Original application filed January 17, 1910, Serial No. 538,519. Divided and this application filed February 4, 1911. Serial No. 606,499.

To all whom it may concern:

Be it known that we, MICHAEL Woods, a subject of the King of Great Britain and Ireland, and residing at 309 Pigdon street, 5 Princes Hill, Carlton, county of Bourke, State of Victoria, Commonwealth of Australia, and THOMAS JEFFERSON GILBERT, a subject of the King of Great Britain and Ireland, and residing at 1 Minnie street, 10 Brunswick, in the county of Bourke, State of Victoria, Commonwealth of Australia, have invented certain new and useful Improvements in and Relating to Machines for Dressing Rails, of which the following 15 is a specification.

This invention relates to machines for dressing rails of the kind in which the dressing means are carried by an attachment which is pivotally secured to the machine as described, for example, in the specification to our copending application Serial No. 538519 filed January 17th 1910.

The object of the present invention is to provide an efficient and readily attachable 25 combined carriage and holder for a tool or tools adapted for use in removing the burs and bevels which occur at the bends or curves in a track having plain headed rails, and also to cut out new and true beds in the 30 rails to permit of the renewal of the fish plates.

The invention consists in a combined carriage and tool holder for use with rail dressing machines adapted to support vertical milling means and to be removably pivoted to the machine about a central longitudinal axis thereof.

One mode of carrying out the invention is illustrated by the accompanying drawings 40 in which—

Figure 1 is an elevation of a combined carriage and holder constructed in accordance with the present invention, and Fig. 2 is a plan view of the same. Fig. 3 is an 45 end elevation of Fig. 1. Fig. 4 is a sectional elevation of a detail.

In all the figures parts have been omitted sectioned or broken away, for the sake of clearness.

50 In carrying out the invention according to one mode, the combined carriage and holder consisting of a framework *a* is provided with removable trunnion caps *b* for accommodating hollow trunnions on the

rail dressing machine, thus permitting of 55 the carriage being removed when necessary. The framework *a* is supported on both sides by flanged wheels *c* each of which is mounted on a pin *d* secured to or formed integral with a slide *e* attached to a screw *f* 60 engaging with a worm wheel nut *g* which can be rotated by means of a worm *h* operated by a hand wheel *i* so that, on turning the hand wheel *i* the flanged wheel is raised or lowered. A removable adjusting piece *j* 65 may be interposed between the framework *a* and the slide *e* for regulating the distance between the wheels so as to suit any gage of rails.

Secured to the framework is an upper 70 cross bar *k* and a lower cross bar *l* upon which is supported at either end a laterally adjustable bracket *m* through which passes a vertical spindle *n* carrying at its lower end a milling tool *o* which receives its motion from any suitable motor carried by the rail dressing machine, the arrangement of the gearing being as follows:—The shaft *p* which passes through the hollow trunnions of the rail dressing machine, is connected 75 at one end to a motor driven shaft by any suitable coupling, and carries at its other end a bevel wheel *q* engaging with one of two bevel wheels *r* slidably mounted on a shaft *s* upon each end of which is a toothed 80 pinion *t* engaging with a toothed wheel *u* carried by a shaft *v* which is journaled in a bearing *v* extending from the bracket *m* and carries a bevel wheel *w* engaging with a bevel wheel *x* mounted on the spindle *n*. 90 The bevel wheels *r* are engaged or disengaged with the bevel wheel *q* in any ordinary way, thus affording a convenient means of reversing the direction of rotation of the cutter. 95

In order to provide means for adjusting the milling tools in a vertical direction, each spindle *n* (see Fig. 4) is provided at its upper end with a collar 18 which rotates within a box 19, suitable packing 20 being 100 arranged within the box so as to form a bearing surface for the collar. Above the box 19 is a spindle *n* supported at its upper end in the bracket *m* and provided at its lower end with a collar 21 which works 105 within the box 19 and is separated from the collar 18 by means of suitable packing 22. The spindle *n* is provided with a screw

thread y engaging with a toothed wheel nut z which engages with a toothed pinion 1 carried on a spindle 2 operated by a hand wheel 3. On turning the hand wheel 3 the spindle n_1 is raised or lowered thus adjusting the tool.

Each bracket m is adapted to slide laterally upon the cross bars k and l and is secured thereto by means of flanges 4 and bolts 9, the necessary adjustment being effected by means of a hand wheel 5 operating a screw 6 which turns within a nut 7 in the framework a and moves the bracket m by means of a collar 8 the shaft v being adapted to slide through the wheel u so as to keep the bevel wheels w and x always in mesh.

When burs and bevels are being treated in plain headed rails alining and steady-
20 ing devices are used. This consists of a bracket 17 attached to the framework a and carrying a roller 11 which makes contact with the inner side of the rail head. Piv-
25 oted at 12 is a bell crank lever having a long spring arm 13 and a short arm 14, the former of which can be adjusted by means of a screw 15, while the latter carries a roller 16 which, by means of the adjusting screw can be brought into contact with the
30 outer side of the rail head.

The tools may treat either side of their respective rails to remodel the head thereof, or by using suitable tools new fish plate beds may be cut out accurately and
35 speedily.

Having now described our invention, what we claim as new and desire to secure by Letters Patent is:—

1. In rail dressing machines, a combined carriage and holder, means for removably and freely pivoting said combined carriage and holder to the machine about a central longitudinal axis thereof, cross bars carried by said combined carriage and holder, brackets supported by said cross bars, a vertical shaft supported by each bracket, a vertical milling tool carried by each shaft, and means for laterally adjusting each bracket upon the cross bars.

2. In rail dressing machines, a combined carriage and holder, vertical milling means carried thereby, means for removably and freely pivoting said combined carriage and holder to the machine about a central longitudinal axis thereof, additional means independent of the machine and of the dressing means for supporting said combined carriage and holder upon the rails being treated, and alining and steadyng means carried by said combined carriage and holder.

3. In rail dressing machines, a combined carriage and holder, means for removably and freely pivoting said combined carriage and holder to the machine about a central

longitudinal axis thereof, cross bars carried by said combined carriage and holder, brackets supported by said cross bars, a vertical shaft supported by each bracket, a vertical milling tool carried on the lower end of said shaft, a collar upon the upper end of said shaft, a box surrounding said collar, a vertical shaft above said box, the lower end of which enters therein, a collar upon said lower end, a toothed wheel nut upon the upper end of said shaft, a toothed pinion engaging with said toothed wheel nut, a shaft carrying said toothed pinion, and a handwheel upon said shaft.

4. In rail dressing machines a combined carriage and holder, vertical milling tools carried thereby, means for removably and freely pivoting said combined carriage and holder to the machine about a central longitudinal axis thereof, cross bars carried by said combined carriage and holder, brackets supporting said milling tools and slidably mounted upon said cross bars, a nut within the framework and adjacent to each bracket, a screw rotating within said nut, a collar upon said screw engaging with the bracket, and a hand wheel operating said screw.

5. In rail dressing machines, a combined carriage and holder, vertical milling means carried thereby, means for removably and freely pivoting said combined carriage and holder to the machine about a central longitudinal axis thereof, and alining and steadyng devices comprising brackets carried by said combined carriage and holder, an inner roller mounted upon said bracket, a bell crank lever pivoted to said bracket, an outer roller carried by one arm of said bell crank lever, and an adjusting screw carried by the other arm thereof.

6. In rail dressing machines, a combined carriage and holder, vertical milling tools carried thereby, means for removably and freely pivoting said combined carriage and holder to the machine about a central longitudinal axis thereof, means for supporting said combined carriage and holder upon the rails being treated, means for vertically adjusting said milling tools, means for laterally adjusting said milling tools, and alining and steadyng devices carried by said combined carriage and holder.

7. In rail dressing machines, a combined carriage and holder, means for removably and freely pivoting said combined carriage and holder to the machine about a central longitudinal axis thereof, a cross shaft driven by the main shaft and carried by said combined carriage and holder, means for reversing said shaft, a toothed pinion upon each end of said shaft, a toothed wheel engaging said toothed pinion, a sliding shaft driven by said toothed wheel, a bevel pinion carried by said sliding shaft, a bevel wheel engaging with said bevel pinion, a

vertical shaft driven by said bevel wheel, and a milling tool carried by said vertical shaft.

8. In rail dressing machines, a combined carriage and holder, vertical milling tools carried thereby, means for removably and freely pivoting said combined carriage and holder to the machine about a central longitudinal axis thereof, flanged wheels supporting said combined carriage and holder, a slide supporting each flanged wheel, and a removable adjusting piece between said slide and the framework of the combined carriage and holder.

In testimony whereof we affix our signatures in the presence of two subscribing witnesses. 15
